Primary Examiner — Ian Simmons*Assistant Examiner* — Carissa C Fitts(74) Attorney, Agent, or Firm — Schwabe, Williamson & Wyatt P.C.(57) CLAIM

The ornamental design for a pocket accent, as shown and described.

DESCRIPTION

FIG. 1 is a front view of a pocket accent, showing our new design;

FIG. 2 is a perspective view of the pocket accent;

FIG. 3 is a front view thereof;

FIG. 4 is a right side view thereof;

FIG. 5 is a bottom view thereof;

FIG. 6 is a back view thereof;

FIG. 7 is a left side view thereof; and,

FIG. 8 is a top view thereof.

The dashed lines are included for illustrating environmental structure and form no part of the claimed design.
